RECEIVER FOR THE ELECTRICAL TRANSMISSION OF INTELLIGENCE

William C. Roe, Elyria, Ohio, assignor, by means assignments, to Printel Communication Systems, Inc., New York, N. Y., a corporation of New York

Application February 5, 1932, Serial No. 591,224

54 Claims. (Cl. 178—34)

This invention relates to systems and apparatus for the transmission of intelligence electrically between remotely situated stations and relates particularly to receiving apparatus and electrical systems therefor situated at the receiving station.

My invention, furthermore, relates to apparatus of this general class, sometimes referred to as telegraphic typewriters.

10 It is an object of my invention to provide an improved apparatus and electrical system therefor whereby electrical energy transmitted thereto from a remote sending station in accordance with a pre-arranged system of impulses and/or groups of impulses may be received and selectively employed to actuate an intelligence communicating apparatus.

Another object of my invention is to provide an apparatus and electrical system of the kind referred to in which the transmitted impulses may actuate a letter printing type selective apparatus whereby, in an improved manner, to translate the impulses into letters and words.

Another object is to provide an improved telegraphic typewriter comprising a type cylinder or the like having a plurality of characters thereon and adapted to be selectively moved rotatively and axially to position it selectively with respect to the characters thereon in selective response to a variety of predetermined electrical impulses transmitted thereto from a remote station.

Another object is to provide a telegraphic typewriter of the class referred to in which the selectively operable type cylinder or the like is combined in an improved manner with a printing mechanism for printing upon a strip of paper the characters successively selected.

Another object is to provide, in a telegraphic typewriter apparatus, comprising a printing ink carrying ribbon, an improved means for repeatedly winding and unwinding the ribbon in alternate directions and for shifting the ribbon transversely to effect a utilization of substantially all of the length and breadth of the ribbon in the typewriting function of the apparatus.

Another object is to provide, in a telegraphic typewriter, an improved means for feeding a printing ribbon and a paper strip through the apparatus during the process of printing characters thereon.

Another object is to provide, in a telegraphic typewriter or the like, in which for the printing of each character on a strip of paper, a plurality of operations are performed successively, improved electrical and/or mechanical means for

timing and "interlocking" the elements of the apparatus to cause the said operations to occur only in a predetermined order.

Another object is to provide, in a telegraphic typewriter, improved means whereby, after a character has been printed, the parts may be returned to their normal position preparatory to printing the next succeeding character.

Another object is to provide, in a telegraphic typewriter or the like, improved means whereby the selection of the characters to be typed may be effected more positively than heretofore, and whereby the selection of the characters, the printing thereof and the return of the parts to their normal position, may be effected in the minimum of time.

Another object is to provide an improved mechanism comprising an element movable to a plurality of selective positions (one specific form of which, for example, is a type cylinder) by movement in two directions (axially and rotatively in the illustrative instance of a type cylinder), and electrically actuated means for thus selectively directionally moving the element responsive to impulses or groups of impulses transmitted thereto from a remotely situated impulse-sending station.

Another object of my invention is to provide in an electrically actuated receiver such, for example, as a telegraph typewriter or the like, and which employs a paper strip upon which characters are printed, means whereby electrical energy transmitted to the receiver as, for example, by a succession of impulses, may actuate the paper strip to move it rapidly through the receiver a predetermined or selected distance at the end of a printing operation thereon, whereby to render visible or more easily legible, the final word or character printed and facilitating tearing off the strip at the end of the printed message received.

Another object is to provide, in an electrically actuated receiver, two or more electro-responsive means which may be actuated severally or jointly by electrical energy transmitted thereto from a distant sending station, and which when actuated severally or jointly, may selectively actuate an intelligence communicating receiver; and which when actuated jointly, effect the said actuation of the receiver irrespective of synchronized or phased mutual relation.

Another object is to provide an intelligence communicating electrically actuated receiver adapted to be actuated by electric energy, for example in the form of impulses, transmitted

5

55

thereto from a distant station, and employing an electric circuit or circuits which may, when not receiving, remain in a dead or unenergized condition and which will respond immediately to 5 effect the intelligence transmitting function upon the transmission thereto of electrical energy from a distant station; and without the necessity of first closing, energizing or otherwise preparing the receiving circuits for the reception of the intelligence communicating impulses or electrical energy.

Another object is to provide in an electrically actuated apparatus, comprising a mechanism actuated by the movable armature of an electromagnet, an improved magnetic circuit for the electro-magnet whereby the minimum of reluctance in the magnetic circuit may be provided and lost motion in the bearing of the armature substantially completely eliminated.

20 Another object is to provide in an intelligence communicating electrically actuated receiver, of the recording type, means whereby upon the changing of electric circuit connections, for example as by throwing a switch, the recorder will record the received message in "code" for purposes of secrecy.

Another object is to provide a telegraphic typewriter operable by a source of energy local to the receiver typewriter mechanism, the energy being released upon the reception by the receiver of a transmitted current impulse or impulses and thereupon operating the receiver through a complete cycle.

Another object is to provide a telegraphic typewriter such as referred to in the preceding paragraph in which at the end of a cycle of operations the entire receiving apparatus is restored to its original receiving condition, and in which during each cycle, mechanical energy is stored therein sufficient for the performance of the next succeeding cycle of operations by power mechanism energized from a local source of electric current.

Another object is to provide such a telegraphic typewriter in which not only is the mechanical energy for each cycle stored in the receiver by the preceding cycle, but also, during the preceding cycle a typewriter ribbon and printing paper tape are stepped ahead a step for the next succeeding cycle.

50 Another object is to provide such a telegraphic typewriter in which electrical impulses received by the typewriter receiving mechanism from a distant sending station effect a selection of intelligence transmitting means (such for example as characters on a printing mechanism), but which impulses also release, for the operation of the mechanism through a complete cycle, energy stored therein by a preceding cycle.

Another object is to provide a telegraphic typewriter of the descriptive properties above mentioned in which the energy stored in the receiving apparatus by a preceding cycle to effect the operation of the mechanism in the next succeeding cycle is only sufficient for said operation of the succeeding cycle, whereby the energy available to operate the mechanism for all cycles is substantially constant as distinguished from mechanisms in which a quantity of energy is stored at one time for a number of succeeding cycles, and therefore being in excess of that required for one cycle and of diminishing amounts for subsequent cycles.

Other objects will be apparent to those who are skilled in the art to which my invention appertains.

My invention is fully disclosed in the following description taken in connection with the accompanying drawings, in which:

Fig. 1 is a view, developed into a plane, of a type cylinder which I may employ in the receiver, of typewriter form, in which my invention may be embodied;

Fig. 2 is an electric circuit diagram illustrating in simplified form an electric circuit or circuits and indicated apparatus therein by which the embodiment of my invention may be actuated;

Fig. 3 is a view, in some respects diagrammatic, illustrating a part of an embodiment of my invention whereby a type cylinder which I may employ may be selectively moved to printing position and returned to a normal position;

Fig. 4 is a fragmentary view taken from the plane 4 of Fig. 3;

Fig. 5 is a view taken from the plane 5 of Fig. 4;

Fig. 6 is a view to an enlarged scale of a ratchet element which I may employ and illustrated in Fig. 3;

Fig. 7 is an elevational view with parts broken away for clearness of an apparatus in which my invention may be embodied and illustrating particularly printing elements and resetting elements forming part of the embodiment; and illustrating also in actual structural form, certain parts illustrated diagrammatically in Figs. 3 to 6 inclusive;

Figs. 8 and 9 are, respectively, fragmentary views of some of the parts of Fig. 7 illustrated in cross-section;

Fig. 10 is a fragmentary view taken from the plane 10 of Fig. 7;

Fig. 11 is a fragmentary sectional view taken from the plane 11 of Fig. 7;

Fig. 12 is a view in some respect diagrammatic of a part of the embodiment of my invention and illustrating a mechanism for controlling movements of a printing tape and of a strip of print-receiving paper;

Fig. 13 is a fragmentary view of a part of Fig. 12;

Fig. 14 is a fragmentary end elevational view of an actual apparatus embodying my invention, which view may be considered as taken from the plane 14 of Figs. 15 or 16;

Fig. 15 is an elevational view of the said actual apparatus embodying my invention, with parts omitted or broken away for simplicity and the view may be considered as taken from the plane 15 of Fig. 14;

Fig. 16 is a top plan view of an actual embodiment of my invention, with parts broken away to simplify the drawings, and the view may be considered as taken from the plane 16 of Fig. 14;

Fig. 17 is a fragmentary view taken from the plane 17 of Fig. 16 and with parts omitted for simplicity;

Fig. 18 is a fragmentary view taken from the plane 18 of Fig. 7 with the parts drawn to a smaller scale approximately half of the scale of Fig. 7;

Fig. 19 is a view similar to Fig. 2 illustrating a modification of a part of the electric circuit which may be employed;

Fig. 20 is a view similar to Fig. 19 illustrating another modification;

Fig. 21 is a view similar to a part of Fig. 7 but illustrating a modification of a rack and pinion mechanism of that figure;

Fig. 22 is a view similar to Fig. 1 but in simpli-

filled form illustrating in diagrammatic form, the mode of operation of a type cylinder which I may employ when the modification of Fig. 21 is employed;

5 Figs. 23 and 24 are electric diagrams indicating some of the circuits which may be employed when a plurality of telegraphic typewriter receivers such as that forming part of my invention are employed in a system of communication.

10 In general, the apparatus in which my invention is embodied comprises a type cylinder 1 mounted for rotary movement on its axis and also for movement longitudinally of its rotary axis. In Fig. 1, I have shown a plane development 15 of the cylinder. The vertical direction represents the longitudinal or axial direction of the cylinder and the horizontal direction the unrolled circumferential dimension of the cylinder. As shown in Fig. 1, the cylinder, in the preferred form thereof, is divided up into forty-two divisions in each of which is or may be provided a type character, number or letter. By rotating the cylinder and/or moving it longitudinally, any one of the characters may be brought 25 into position to be printed upon a strip of paper, all of which will be fully set forth hereinafter.

The division 2 on the cylinder is the division to which the cylinder is moved when it is desired to provide a space between successive words being 30 printed from the characters; and the division 3 is the division with respect to which the cylinder is positioned when in its normal position, or the position to which it returns after the character has been printed.

35 The mechanism to be fully described herein-after for rotating and reciprocating the type cylinder 1 is actuated by electrical impulses transmitted to the apparatus from the remote or sending station. Preferably, the impulses are 40 transmitted over two circuits, the impulses on one circuit functioning to rotate the type cylinder 1, and those of the other functioning to move it longitudinally; and in either case, the apparatus responds to each single impulse to rotate 45 the cylinder a single space or division or to move it longitudinally a single division.

Thus, for example, three successive impulses on one circuit would, referring to Fig. 1, move the cylinder longitudinally (vertically) to bring 50 the character M in position to be printed. At the same time, however, if there were three successive impulses in the other circuit, it would rotate the cylinder (horizontally) to bring the character L into position to be printed. Or, if there 55 were no impulses on the first circuit but there were three impulses on the second circuit, it would bring the character H into position to be printed, the movement starting, in each case, from the division 3.

60 The impulses from the sending station may be transmitted to the receiver embodying my invention over two wires with a common return wire or with a ground return circuit.

Referring now to Fig. 2, which illustrates in 65 simplified form, a diagram of various electrically actuated devices and circuits thereof forming part of the preferred embodiment of my invention, I have shown at 4 and 5 incoming lines over which impulses are transmitted from the sending station, and at 6 a return wire or a connection to ground. At 7 and 8 are a pair of selecting electro-magnets which, through suitable mechanism, and in response to impulses received over the lines 4 and 5, respectively and selectively, rotate the 75 type cylinder 1 and move it axially.

At 18' is a relay, the magnet 10 of which is connected in series respectively with the magnets 7 and 8 by a wire 11 and completing their circuit through the line 6. Thus the impulses which energize the magnets 7 and 8 respectively also energize the magnet 10 and hold open the relay 18' so long as the impulses continue. Upon cessation of impulses, the relay contacts 17-17 are sprung closed.

5 At 13 is a printing magnet which when actuated 10 effects, through suitable mechanism, a printing of the characters selected on the type cylinder by the selecting magnet; and at 14 is an electromagnet which when energized re-sets all of the apparatus to its original or normal position prior 15 to the reception of a set of character-selecting impulses.

The printing magnet 13 is energized from a local source such as a battery 15, the current flowing through a wire 16 and through the contacts 20 17 of the relay 18', by wire 19, through a switch arm 128, switch contact 20, switch arm 126, and by wire 21 to and through the magnet 13 and back to the battery 15 by a wire 22. At the same time, current flows by way of the wire 21 through wire 25 30, a lamp 23, wire 24 and thence through the winding of the magnet 14, and by way of a wire 25, to the wire 22 and battery 15. Thus upon closure of the relay 18' at contacts 17, the magnet 13 is fully energized to effect an operation of the 30 mechanism controlled thereby, and the winding 14 is partially energized in series with the high resistance of the lamp 23.

Upon energization of the printing magnet 13, it operates the printing mechanism not shown in 35 the diagram, and also actuates a switch arm 26 which closes a switch contact at 27 and opens the contact at 20. This causes the current flowing in the wire 19 to flow through the contact 27 and thence, by a switch arm 127, wire 28 and wire 24, 40 directly to the magnet 14, giving it full energization, and places the lamp 23 in the circuit of the winding 13 which is now energized by way of the contact 27, wire 28, lamp 23, and wire 30, greatly reducing the energization of the winding 13.

45 Full energization of the winding 14 thus effected operates a resetting or restoring mechanism associated therewith and also actuates a switch arm 31 having an extension 158 which opens the contact 17. The latter contact, which controls the main circuit to the battery 15, 50 interrupts the current to both the magnets 13 and 14, to completely de-energize them and to restore their switch contacts and the mechanism actuated by the magnets to their original or normal positions, and the contacts 17 are held open by a latch 17'.

To insure a positive full stroke movement and to avoid chattering at the contacts 17, a momentary shunt circuit through wire 9, switch arm 12 and switch contact 29 is made around the contacts 17 by movement of the switch arm to closed position during the attracted movement of the arm 31. A one-way trigger 32 closes contact 29 momentarily during the first part of movement of the arm 31 and permits it to open during latter part of the stroke, whereupon all current from the battery 15 is interrupted and magnets 13 and 14 de-energized; upon the return of arm 31, the trigger 32 rotates and avoids closing of the contact 29 in a well known manner.

65 This completes one cycle of operations for the printing of one character. Upon the performance of the resetting or restoring operation above referred to, the latch 17' is withdrawn by means 70 75

associated with the resetting mechanism, and not illustrated in the diagrammatic showing of Fig. 2, so that the contacts 17 can close and so that upon the next energization of the magnet or magnets 5 7 and/or 8, another cycle may be initiated.

The diagrammatic apparatus, Fig. 2, for controlling the circuits as just described, differs, for the sake of simplification, from the actual apparatus of subsequent figures, but only in such respects as will be clearly understood by those skilled in this art.

Thus upon the reception of impulses by the magnets 7 and 8, the relay 18' is held with the contacts 17 in open condition by the current impulses flowing in the magnet 10, suitable electrical and/or mechanical inertia being provided in the relay 18' to prevent its releasing the armature 94 and the contacts 17 so long as impulses are flowing. Upon the cessation of the impulses, the relay 18' being de-energized, permits the contacts 17 to close, causing an energization of the magnet 13 to effect the printing operation and this is immediately followed by energization of the magnet 14 to restore the entire mechanism to its normal position and to restore the circuit to its de-energized condition.

The mechanism actuated by the various electro-magnets above described will now be considered. In Figs. 3 and 12, I have illustrated in semi-diagrammatic form an apparatus embodying the general principles of my invention, and in the remaining figures have illustrated the same mechanism but more as it actually appears in a preferred form when produced for practical or commercial purposes.

Referring to Fig. 3, I have reproduced at 7 and 8 the impulse-receiving magnets, each having associated therewith an armature, 35 and 36, pivotally supported at 37-37, one end of each being adapted to be attracted by the magnet and the other end of each having a finger 38-38 engaging an arm 39-39 of a pair of bell cranks 40-40, pivoted at 41-41. The other arms 42-42 of the similar bell cranks 40 are bifurcated at their free ends to provide fingers 43 and 44, provided each at the free ends thereof with downwardly projecting pawls 45 and 46. These pawls straddle elongated longitudinally movable ratchet pieces 47-47 provided on their lateral edges with longitudinally extending rows of teeth 65 and 66 respectively, engageable by the pawls 45 and 46.

Extending downwardly from the ratchet pieces 47-47 are pins 67-67 engaged upon their rearward sides by the upper free ends of springs 68-68, see Figs. 7 and 11. The springs 68 are preferably formed from flat steel strips and supported and disposed to exert a forward resilient thrust on the pins 67, thrust portions 69-69 being provided on the upper free ends of the springs 68 and interposed between the springs and the pins 67, whereby, in all relative operative positions of the pins 67 and springs 68, the thrust of the spring may be transmitted from the upper extreme end of the spring.

The lower ends of the springs 68 are rigidly connected as by screws 70 to a head 71 rotatably supported in ball bearings 72, but adapted, in a manner to be described, to take up a normal position such as that illustrated in Fig. 7, in which the springs 68 are bent to continuously exert a forward thrust on the pins 67 and the ratchet pieces 47.

In connection with the apparatus thus far described, when a magnet such as the magnet 7 is

energized with one or more impulses, the armature 35 thereof will be rocked clockwise and correspondingly rock the bell crank 40 counter-clockwise against the clockwise torque of a spring 75. The spring 75 normally maintains the pawl 45 against the teeth 65, and the pawl 46 out of engagement with the teeth 66, and the ratchet pieces 47 are continuously resiliently pressed forward by the springs 68 as above described. Therefore, upon energization of the magnet 7, say, by one impulse, the pawl 45 will be moved out of engagement with its engaged tooth 65, and the pawl 46 will be moved into engagement with a tooth 66 to transfer the ratchet piece holding function from the pawl 45 to the pawl 46.

When the magnet 7 is de-energized at the end of the said impulse, the spring 75 returns the pawl 45 toward the teeth 65, but the rearwardly inclined edge, such as the edge 76, of the tooth 66, permits a slight forward movement of the ratchet piece 47 during the inward movement of the pawl 45 and outward movement of the pawl 46 so that during the return of the pawl 45 toward the ratchet piece 47, the ratchet piece 25 may be moved forwardly a small distance by the spring 68 so that the pawl 45, as it returns, engages the next succeeding tooth 65 and the ratchet piece 47 will thus be advanced a distance corresponding to one tooth space. Thus also, 30 upon energizing the magnet 7 with a succession of impulses, the bell crank 40 will be vibrated back and forth, in one direction by the magnet 7 and in the other by the spring 75, and the ratchet piece 47 will be stepped forwardly 35 rapidly a corresponding number of teeth or steps.

In the forward ends of the ratchet pieces 47 are provided upstanding pins 48 over which are looped links 49 and 50 having elongated slots 40 78 and 79 respectively therein. At the outer free end of the link 49 is pivoted as at 51 the arm 52 of a bell crank 53 pivotally mounted at 54. A spring 55 constantly exerts a counter-clockwise torque on the bell crank 53. The other arm 63 45 of the bell crank has a head or pin portion 80 disposed in the annular groove 81 of a shifting head 82 formed integrally with or connected to the type cylinder 1, axially movable upon a supporting shaft 83 but splined or otherwise 50 connected therewith to rotate with the shaft 83. The shaft 83 is supported in adjustable rotational bearings 84 and 85.

As will now be apparent, when the upper ratchet piece 47, as viewed in Fig. 3, is stepped 55 forwardly as above described, the pin 48 will advance in the slot 78 of the link 49 or tend to advance therein due to the exceedingly rapid forward movement of the pin 48 and due also to the stepped or intermittent character of its movement. At the same time, the spring 55 will rock the bell crank 53 counter-clockwise and move the type cylinder 1 along the shaft 83, the extent of the movement being determined by the extent of movement of the pin 48 which in turn 65 is determined by the number of teeth or steps of advancement of the ratchet piece 47.

By means of the link and pin connections, 48-49, the intermittent movement of the ratchet piece 47 may go on freely unhampered by the 70 inertia of the type cylinder and the parts connecting it with the ratchet teeth, and these latter parts may move with a steady or continuous movement, effected by an independent source of power, namely the spring 55. At the end of 75

movement of the ratchet piece 47, whereat the end of the slot 78 engages the pin 48, the type cylinder 1 is accurately brought to rest at a position corresponding to the movement of the ratchet piece 47, which, in accordance with the selective number of impulses, positions the cylinder longitudinally with respect to a character thereon.

At the outer end of the link 50, a rack bar 55 is connected, and mounted to move longitudinally in unison with the link 50. A connecting rod 57 is pivotally connected to the rack bar 55 at 56 at one end and at the other end is pivoted as at 58 to a crank arm 59 pivotally supported at 60. A spring 61 continually exerts resilient torque clockwise on the arm 59 and thus, acting through the connecting rod 57, exerts a longitudinal resilient thrust toward the left as viewed in Fig. 3, on the rack bar 55. The rack bar 55 has rack teeth 87 on the under side thereof meshed with the teeth of a gear 88 secured to the shaft 83 in any suitable manner and rotatable therewith.

As will now appear, when the ratchet piece 47, the lower one as viewed in Fig. 3, is projected forwardly with the intermittent rapid movement above described, the pin 48 thereof will advance in the slot 79. Concurrently therewith, the link 50 and rack bar 55 will be pulled forwardly with a steady or continuous movement by the spring 61, thereby rotating the gear 88 and the shaft 83 and the type cylinder 1; and the extent of the rotational movement of the type cylinder 1 will be determined by the extent of movement of the ratchet piece 47 and pin 48, the movement being finally stopped, after the ratchet piece 47 stops moving, by engagement of the end of the slot 79 with the pin 48; and the rapid intermittent movement of the ratchet piece 47 will not be interfered with by the relatively great inertia of the other parts mentioned, associated therewith, but the rotary movement of the type cylinder 1 will be accurately determined and will rotate the type cylinder 1, one or more divisions thereof as described hereinbefore in connection with Fig. 1.

Since it is desired for each impulse in the magnets 7 and 8 to respectively rotate the type cylinder 1 by an amount equal to one division thereof as shown in Fig. 1, and to move it longitudinally an amount equal to one division, the pitch 50 diameter of the gear 88 must be proportioned so that it will turn the type cylinder 1 one division for each tooth or each step movement of the corresponding ratchet piece 47; and the ratio of the length of the bell crank arms 52 and 63 must be 55 proportioned so that the longitudinal movement given to the type cylinder 1 will be correct for one complete division thereof for each tooth space or step of movement of the ratchet piece 47.

Where, as illustrated in Fig. 3, the longitudinal movement of the type cylinder 1 is in a direction at right angles to the longitudinal movement of the ratchet pieces 47, the bell crank arms 52 and 63 are preferably disposed at substantially a right angle to each other and the pivot point 54 is preferably disposed so that the total movement of the bell crank arm will be substantially equal amounts on the opposite sides of corresponding center lines; for example, the bell crank arm 63 may move from one extreme position to the other, equal amounts on opposite sides of a horizontal line through the pivot 54, and the bell crank arm 53 correspondingly will move substantially equal amounts on opposite sides of a vertical center line through the said pivot.

By this provision, equal steps on the ratchet

pieces 47 will effect equal steps on the type cylinder 1. At the same time, the bell crank arm 63 may be longer than the bell crank arm 52 whereby any desired magnification of movement of the type cylinder 1 may be effected in correspondence to any suitable distance between the steps of the ratchet pieces 47. Again, if it be desired to move the type cylinder 1 unequal amounts as, for example, where some of the characters may occupy more longitudinal length on the cylinder, correspondingly the teeth spaces on the ratchet pieces 47 may be variable. Furthermore, although the lever arm 52 moves around a supporting pivot 54 and therefore its angular movement for two steps adjacent the left-hand end of the ratchet piece 47 is greater than for successive teeth, nevertheless, by the arrangement of the lever arms above described, this is exactly compensated for in the movement of the type cylinder 1; and for equally spaced teeth on the ratchet piece 47, the steps taken by the type cylinder 1 will be equal.

Referring again to Fig. 6, which illustrates one of the ratchet pieces 47 to an enlarged scale, I have shown the preferred form of the teeth 65 and 66. The teeth 65 comprise each a pawl-engaging portion 65' disposed substantially at a right angle to the direction of movement of the ratchet piece 47 and a rearwardly inwardly inclined portion 65'' disposed at an angle of approximately 45° with the portion 65'. The teeth 66 comprise each a pawl-engaging portion 66', rearwardly outwardly inclined at an angle of approximately 30° from the direction of movement and a rearwardly inwardly inclined portion 66'' at an angle of approximately 45°, the shape of the teeth 65 and 66 thus provided being clearly illustrated in Fig. 6. I find that teeth of these forms cooperate more effectively and positively in conjunction with the pawls 45 and 46 respectively than other shapes, but as will be understood by those skilled in the art, the teeth 65 and 66 may be, in form, considerably varied from that illustrated in Fig. 6 without detracting unduly from a positive accurate ratcheting function.

The type cylinder 1 may be mounted on the shaft 83 to rotate and move axially thereon by various mechanical arrangements, but I prefer the construction illustrated in Figs. 3, 4, and 5. As illustrated in these figures, the type cylinder has longitudinal grooves between the longitudinally disposed series of character supporting portions. In one of these grooves is disposed a key 82' preferably in the form of a slender rod, an end of which is mounted slidably in a bore 81' in the head 82, and is secured at one end in a suitable recess in a flange 83' of the gear 88. The key 82' is thus rigidly connected to the gear 88, rotates with it and forms a key or feather for guiding the longitudinal movements of the type cylinder 1, and also serves as a means to rotate the type cylinder 1 to communicate thereto rotary or oscillatory movement of the gear 88.

By this construction, the key or feather 82' may be disposed at a relatively great radial distance from the shaft 83 to reduce to a negligible amount any tendency of the cylinder 1 to jam thereupon; and the type cylinder 1 may be relatively loosely mounted upon the shaft 83 and have a relatively loose engagement with the key 82' whereby the type cylinder may in every case move freely and with great rapidity to its selected position.

As described in connection with Fig. 2, the impulses of current energizing the magnets 7 and

- 8 also energize the magnet 10. When energized the magnet 10 attracts an armature 89 pivotally supported at 90 and provided on its free end with an anti-friction wheel or roller 92 engaging 5 an inclined portion 93 of a resilient switch arm 94 having a contact 17 adapted to electrically engage a second contact 17 on a stationary switch arm 97. The magnet 9 and the parts just described constitute the relay 18 of Fig. 2.
- 10 The armature 89 is maintained in its counter-clockwise position against the tension of a spring 89' by the engagement therewith of one arm 91 of a bell crank 98 pivotally supported at 99. The other arm 100 of the bell crank carries, pivoted 15 at its free end as at 104, an equalizing bar 105 bridging and engaging the pins 48.

Upon energization of the magnets 7 and 8 by impulses, these impulses energize the magnet 10 and attract the armature 89, freeing 20 it from the end of the bell crank arm 91. When, as above described, the pins 48—48, either or both of them, move forwardly, they will leave their engagement with the equalizing bar 105 and the bell crank 98 will be free to be rotated 25 clockwise around its pivot 99 as, for example, by a tension spring 106, to a position such as that in broken lines at 90'. When the impulses cease, the energization of the magnet 10 ceases and the spring 89' will retract the armature 89, causing 30 the roller 92 to leave the inclined portion 93 of the switch arm 94 and causing the contacts 17—17 to close the circuit through the wires 16 and 19 as described for Fig. 2.

The movement of the armature 89 will be 35 stopped on the end of the arm 91.

When the bell crank is rotated counter-clockwise upon the restoring of the ratchet piece 47 in a manner to be described, the end of the arm 91 will engage and slide over a cam surface 101 40 on the armature 89 moving it counter-clockwise to open the contacts 17—17 and will hold it in this position by engagement with the armature 89 on the relatively elevated portion 102.

As described in connection with Fig. 2, closing 45 the contacts 17 will cause energization of the magnet 13, which has been called the printing magnet. As shown in Fig. 7, the magnet 13 has a magnetic circuit of E-form and the three poles 108 thereof cooperate to attract a magnetic armature 109 pivotally supported at 110, and the movement or stroke of which may be adjustably regulated by a rearward extension 111 of the armature and two abutments 112—112 on opposite sides of the extension and supported in a 50 bracket 113 and independently movable toward or from the extension as by screw threads thereon. The opposite end of the armature 109 carries an upwardly extending threaded stud 114 which may be adjustably secured in the end of 55 the armature 109 by being threaded therethrough and locked thereon by a lock nut 115. The upper end of the stud 114 is surmounted by a head 116 provided with a shock absorbing disc 117.

A plunger 118 threaded at its extreme lower 60 end as at 119, rests upon the disc 117 and is guided for axial reciprocatory movement in a sleeve 120 which may be suitably supported upon a main frame element as at 121, Fig. 8. On the lower end of the sleeves 120 is adjustably screw-threaded a thimble 122 through a perforation in the closed end of which the plunger 118 may reciprocate, and a nut 123 surmounted by a shock absorbing disc 124 is threaded onto the lower end 65 of the plunger 118.

75 The type cylinder 1 is disposed directly above

the upper end of the plunger 118, the normal positions of the type cylinder 1 and plunger 118 being indicated in Figs. 3 and 7. A strip of paper 125 upon which the characters are to be printed and which is dispensed in a manner to be described, is disposed between the plunger 118 and the type cylinder 1, and a printing ribbon 184, adapted to be wound and unwound and transversely shifted in a manner to be described, is disposed between the paper strip 125 and the 10 type cylinder 1 as illustrated in Figs. 8 and 9.

In a manner that will now be apparent, when the magnet 13 is energized, the armature 109 will be attracted and the upward movement of its free end carrying the head 116 will be communicated to the plunger 118 and cause the upper end thereof to strike a blow which will drive the paper strip 125 and ribbon 184 against a selected character on the type cylinder 1 and imprint this character on the paper strip. In Fig. 8 are illustrated the positions of the parts at the moment of imprinting a character; and in Fig. 9 is illustrated the position of the parts when the division 2, Fig. 1, of the type cylinder is the selected position, whereat, as will be seen in Fig. 9, the upper 25 end of the plunger 118 is stopped short of a printing position by the impinging of the disc 124 and nut 123 upon the lower end of the thimble 122. To further insure a blank space between successive printed words, the "space" division 2 of 30 the cylinder 1 is depressed as shown at 2' in Fig. 9.

The stroke of the plunger 118 when printing characters may be adjusted by the stud 114 to leave a slight clearance between the disc 124 and 35 the lower end of the thimble 122 to insure a suitable impact on the type; and the stroke when a space is desired between words, may be adjusted by adjusting the thimble 122 to suitably stop the plunger by the disc 124; and the impact of the 40 plunger 118 may be regulated by adjustably providing a clearance between the end 119 of the plunger and the disc 117, as shown in Figs. 8 and 9.

As shown in connection with Fig. 2, the operation of the printing magnet 13 breaks a circuit at 20 and makes a circuit at 27, and this is effected in the preferred embodiment of my invention as illustrated in Fig. 7. Three resilient switch arms 126, 127, and 128 are secured as by screws 50 129 to a sliding support 130 on the frame of the magnet 13 and adjustably positionable thereon by slots 132 in the support and screws 131 in the slots in a well known manner. The resilient switch arms are insulated from each other and 55 from the support 130 by insulating blocks 133—133. As viewed in Fig. 7, the resilient switch arms depend toward the armature 109 and the arms 126 and 128 have a pair of normally mutually engaged contacts 20—20 and the arms 127 and 128 have a pair of normally normally disengaged contacts 27—27. The arm 127 extends beyond the other two arms and has an inclined portion 134 thereon engaging with a roller 135 60 rotatably mounted on the armature 109.

Upon upward or counter-clockwise movement of the armature 109 around its pivot 110, to effect the printing operation above described, the roller 135 moves the switch arm 127 to effect the 70 engagement of the contacts 27—27 and subsequently to effect disengagement of the contacts 20—20 whereby, as described in connection with the wiring diagram of Fig. 2, the restoring magnet 14 is energized and the printing magnet 13 75

is partly de-energized by inserting in series therewith the high resistance lamp 23.

By suitably spacing the contacts 27-27, the energization of the magnet 14 from the partial energization thereof through the lamp 23 to the full energization thereof may be initiated as early in the stroke of the armature 109 as may be desired to insure that the magnet 14 will be fully energized at the termination of the stroke of the armature 109 and of the plunger 118.

The function of the restoring magnet 14 is, as stated above in connection with Fig. 2, to restore the parts mechanically and electrically to their original or normal condition. This will now be described. It will be observed that at the time of energizing the magnet 14, the type cylinder 1 is in some one of its selective positions and therefore the ratchet pieces 47-47 are in one or another of their forwardly stepped positions; and that the printing plunger 118 is retained generally in its upper or printing position by the magnet 13, but with the end 119 of the plunger resting by gravity on the disc 117.

A depending armature 138, Fig. 7, is pivotally mounted as at 139 to swing toward and from the magnet 14, a pole piece 140 being provided on the armature 138 upon which the flux of the magnet 14 may act. The lower end of the armature 138 is pivotally connected to the two legs 141-141 of a U-shaped link 142, a pin 143 extending through the legs of the link and through the armature 138. A slot 144 in the legs 141 permits longitudinal movement of the ends of the pin 143 therein and a spring 145 is placed between the lower end of the armature 138 and the closed end of the link 142, whereby movement of the armature 138 may be initiated in quick response to the energization of the magnet 14 and without waiting for the inertia of the associated parts to be overcome, and movement of the armature transmitted to the link by the armature 138 may be cushioned to avoid shock, and, for purposes of absorbing inertia of parts connected to the link 142, to permit the full stroke of the armature 138 to precede the movement of the said moved parts.

The legs 141 of the link 142 are pivotally connected as at 146 to the lower end of a lever 147 pivotally supported intermediate its ends and adjacent the pivot 146 on a ball bearing support 72. The opposite end of the lever 147 more remote from the bearing 72 is, as shown in Figs. 7 and 11, provided with a transverse bar 148 normally disposed forwardly of the pins 67 which depend from the ratchet pieces 47. And the lever 147 is also provided with a laterally extending pin 149 between the bar 148 and the bearing 72.

Upon attraction of the armature 138 by the magnet 14 in the clockwise direction as viewed in Fig. 7, movement is transmitted through the link 142 to the lever 147, rocking it clockwise around the bearing 72, causing the bar 148 to move to the right and engage the pins 67 in whatever forward position they may have been selectively disposed, and to move them back to their normal position, during which movement the pins 48 and the links 49 and 50 operate through the bell crank 53 and through the rack bar 55 to restore the printing cylinder 1 to its normal position. The springs 55 and 61 continuously act tending to move the links 49 and 50 forwardly and thus, acting through the pins 48, exert forward thrust on the ratchet pieces 47-47, but upon the completion of the rearward movement of the ratchet pieces 47 by means of the lever 147 as described,

the ratchet pawls 45-45 will retain the ratchet pieces 47 in their rearmost or normal position.

The rearward movement of the pins 48 acts upon the equalizing bar 105 to rock the bell crank 98 counter-clockwise causing the end of the arm 91 thereof to move over the cam 101 against the tension of the spring 106, into a position to engage the portion 102 of the armature 99 in which position it may be subsequently held by a shoulder 102' on the armature. Thus the contacts 17-17 are opened and held open.

As will presently be referred to again, the magnet 14 will be de-energized after the lever 147 has moved through its stroke to reset the ratchet pieces 47, and to retract the lever 147 to a position suitable for its next operation, a spring 147' is provided connected at one end to the lever 147 and at its opposite end to a suitable point on the stationary frame of the apparatus, the spring functioning to exert a counter-clockwise torque on the lever 147. When the ratchet pieces 47 have been restored to their reset position and held there by the pawls as above described, the springs 68 are under tension and by their own reaction upon the head 71 tend to rotate the lever 147 clockwise in opposition to the tendency of the spring 147'. When the ratchet pieces 47 are ratcheted ahead, the tension in the springs 68 is gradually released, enabling the spring 147' to over-power the springs 68 and retract the lever 147. By suitably proportioning the tension of the springs 68 and 147', so that they suitably counter-balance each other, the retractive effort of the spring 147' will only be able to retract the bar 148 a relatively short distance from the pins 67, and as the pins advance with the ratchet pieces 47, the bar 148 will retreat ahead of them so that the bar 148 is at all times a relatively constant and relatively small distance away from the pins. Therefore, at each energization of the magnet 14 and resetting movement of the bar 148, the bar 148 moves only a short distance to engage the pin 67 whether the ratchet pieces have been moved ahead one notch or one tooth, or the complete range of teeth; and therefore the bar 148 engages the pins with the minimum of impact. The lever 147 thus has a floating movement which maintains the bar 148 in readiness to effect a resetting action in the minimum of time after energization of the magnet 14, as well as with the minimum of shock.

The mechanism for moving the paper tape step by step as successive characters are printed thereon, and the mechanism for moving the printing ribbon to bring a fresh portion thereof in position for use to print each successive character will now be described. At each operation of the mechanism actuated by the restoring magnet 14, the tape and ribbon mechanism referred to is actuated through one complete cycle and the power for its operation is taken from the restoring magnet 14 in the following manner.

Upon movement of the lever 147 clockwise as viewed in Fig. 7 or counter-clockwise as viewed in Fig. 12, a transverse bar or pin 149 on the lever engages one arm 153 of a three-arm bell crank 152 and rotatively moves the bell crank around a pivotal support 154. A second arm 167 of the bell crank 152 has a roller 166 on its free end engaging a flat spring 165 and by movement of the arm 167 carries the spring downwardly, see Fig. 12, into engagement with the lever 168, and by a continuation of movement gives to the lever a slight rocking or rotational movement counter-

clockwise about a lever-supporting pivot 169. Upon retraction of the arm 167 or upon disengagement from the bell crank 152 of the pin 149, the lever 168 is retracted by a spring 168', and thus the lever 168 is given an intermittent oscillatory movement around its support 169; and it is this movement which actuates the tape and ribbon mechanism and which will now be described in detail with particular reference to Fig. 12.

10 Pivots connected to the left end of the lever 168 as at 171 is one end of a depending link 170, the lower end of which, as at 172, is pivotally connected to a pawl arm 173 which in turn is pivotally supported at 174. Upon each downward movement as viewed in Fig. 9 of the said end of the lever 168, the pawl arm 173 is given a corresponding clockwise movement causing a pawl 175 on the end thereof engaged with teeth 176 of a ratchet wheel 177 to step ahead the wheel 177 one tooth. Connected to the wheel 177 is a feed roller 178 between which and a corresponding mating roller 179, the strip of paper 125 upon which the characters are to be printed is disposed.

The two rollers are maintained in pressure relation on opposite sides of the tape by a spring 181 anchored at one end at 182 and at its free end engaging resiliently the shaft 183 upon which the roller 179 is mounted, thus pressing the roller 179 firmly toward the roller 178 and causing the roller 178 to grip the paper strip 125 by its frictional contact therewith whereupon the roller 178 may feed the strip 125 positively.

The plunger 118 hereinbefore described is illustrated in this figure disposed below the paper strip 125, and above the strip is illustrated a portion of the type cylinder 1. When the plunger 118 is moved upwardly, it strikes the paper strip and carries it against the printing ribbon 184 and carries the latter against a character on the type cylinder, thus printing a character on the paper; and after the printing of each character, the plunger 118 is restored to its lower position as above described, and the paper strip is fed longitudinally a step as above described preparatory to printing the next character.

The printing ribbon 184 which may be of the well known typewriter ribbon form is wound upon a drum 185 and may be unwound therefrom by winding the other end thereof on a similar drum 186. The intermediate portion of the ribbon 184 between the drums is led over a pair of rollers 187—187 to dispose it in a plane parallel to and in close proximity to the paper strip 125, and the ribbon is guided onto the rollers 187 by passing through perforations 188—188 on opposite sides of the rollers 187, the perforations being formed in a sheet metal guide 189. The rollers 187 are supported on the guide 189 by depending hangers 190 having at their lower ends oppositely disposed ears 191—191 in which supporting shafts 192 of the rollers 187 are rotatably mounted. Thus the perforations 188 are disposed so as to feed the ribbon 184 to the rollers, and when the ribbon 184 is shifted laterally in a manner to be described to distribute the wear of the printing operation over the ribbon, the rollers 187 and perforations 188 may be moved in unison by movement of the guide 189.

A bell crank 195 is pivotally supported as at 196 on an end of the lever 168 and comprises a depending arm 197 and a generally horizontal arm 198. The arm 198 is bifurcated as at 199 at the end thereof and in the bifurcation is disposed the end of a hairpin-form spring 200, the other end of which is anchored as at 201 upon

the arm 168. A relatively slight rotational movement of the bell crank 195 on its pivot 196 will throw the bifurcation 199 above or below, respectively, the center line of the pivots 196 and 201, and the spring 200, acting in a well known manner, will resiliently hold the arm 198 in either position above or below the center line and correspondingly hold the arm 197 resiliently toward the left or toward the right as viewed in Fig. 12.

10 The free end of the arm 197 is provided with a pair of opposite pawls 202 and 203, the pawl 202, in the position of parts illustrated in the drawings, being disposed in a tooth space of a ratchet wheel 204; and the pawl 203 is disengaged from similar ratchet teeth of a similar ratchet wheel 205. A ratchet pawl 206, pivotally supported at 207, has on its lower end a pair of pawl teeth 208 and 209, the tooth 208 being engaged in a tooth space of the ratchet 204, and the tooth 209 being out of engagement with and spaced from the teeth of the wheel 205.

15 As will now appear, the aforesaid intermittent oscillation of the lever 168 will cause the arm 197 to reciprocate upwardly and downwardly as viewed in the drawings, and this movement will cause the tooth 202 to ratchet over the teeth of the wheel 204 and then to step it ahead, the tooth 208 preventing the wheel from overtraveling or from moving during ratcheting of the tooth 202 20 in a well known manner. The spring 200 besides functioning as a throw-over spring as above described, functions also as a "click" spring for the ratchet wheel 204 to hold the tooth 202 resiliently against the wheel teeth.

25 By means of a gear 210 on the ratchet wheel 204 or associated therewith and meshed with a gear 211 on a shaft 212, the shaft may be rotated step by step. The drum 186 is on the shaft 212 and thus, step by step, winds the ribbon 184 30 upon the drum 186. The ribbon 184 so wound is being unwound from a similar drum 185. A follower 213 comprising an arm 214 secured to a shaft 215 at one end and carrying at its other end a roller 216, causes the roller to follow the 35 decreasing diameter of the unwinding ribbon 184 upon the drum 185, causing the shaft 215 which is mounted in suitable supporting bearings to rotate step by step. On the opposite end of the shaft 215 is a radially projecting hook device 217 40 provided with a hook 218 at its end. Continued rotation of the shaft 215 will bring the hook 218 gradually under an ear 219 on the bell crank arm 197; and when this condition has been reached, the next successive downward reciprocation of 45 the bell crank arm 197 will cause the ear 219 to pivot on the point of the hook 218 and rock the bell crank 195 around its pivot 196 and shift the arm 198 sufficiently to cause the spring 200 to snap it beyond the center line whereupon the 50 bell crank arm 197 will be thrown laterally toward the right and bring the tooth 203 into engagement with the teeth of the ratchet wheel 205 after which, movement of the bell crank arm 197 upwardly and downwardly, as above described, 55 will ratchet the ratchet wheel 205 step by step. This will effect a winding of the ribbon 184 upon the drum 185, reversing its direction through the frame 189. The pawl 206 at the same time is 60 swung over to engage its tooth 209 with the ratchet wheel 205 by means of a hairpin-form spring 220 anchored at the closed end thereof at 221 upon the pawl 206, and the free ends of the hairpin form being resiliently compressed between the teeth 202 and 203 on the arm 197.

70 75

Movement of the arm 197 in either direction will transmit its movement through the hairpin to the pawl 206 and move it resiliently into engagement with one or the other of the ratchets 204 or 205, as the case may be.

5 In either position of the pawl 206, the hairpin spring 220 besides functioning to move the pawl 206 as described from side to side, thereafter functions as a "click" spring to maintain the 10 pawls 208 or 209, as the case may be, in resilient ratcheting engagement with the ratchet wheels 204 or 205.

The ratcheting of the ratchet 205 goes on until the ribbon has unwound from the drum 186 sufficiently to cause a follower 222 and shaft 223 to move a hook device 224 similar to the hook device 217 into position to be engaged by an ear 225 similar to the ear 219 described, whereupon the bell crank arm 197 will be rocked back again into 20 the position illustrated to ratchet the ratchet wheel 204 in a manner described.

Thus the ribbon 184 is repeatedly wound upon one of the drums 185 or 186 and then unwound therefrom and wound upon the other drum.

25 In order to maintain the shafts 215 and 223 constrained to rotate in the proper direction, a spring 217', see Fig. 13, is connected to the hook devices 217 and 224, thus at all times applying a resilient torque to the shafts.

30 The spring 217' may also, as illustrated in Fig. 13, function to hold the arm 214 away from the drum 185 as, for example, when it is desired to change a ribbon on the drum. As illustrated in Fig. 13, when the shaft 215 is rotated through 35 somewhat more than a fourth of a revolution, the right hand end as viewed in Fig. 13 of the spring 217' passes beyond the center line of the shaft 215 and, in a well known over-center manner, resiliently holds the shaft in its rotated position.

During the first winding revolution of each drum, means is provided, now to be described, to shift the ribbon transversely in alternate directions, whereby when the ribbon is traveling in one direction, the printing operation will be effected thereon on portions at one side of the center line and when in the other direction, on portions on the other side of the center line to distribute the wear on the ribbon.

50 Referring to the drum 186 upon which the ribbon is wound as viewed in Fig. 12, the shaft 212 which rotates the drum 186 carries a disc 225 having a tooth 226 in the periphery thereof. A rod 227, generally horizontally disposed, has a hook 228 on its left end as viewed in the drawing, and the opposite end is pivotally connected as at 229 to an oscillating arm 230 pivotally supported at 231, and provided on its lower end with a cam follower 232.

60 The hook 228 is disposed in the path of the tooth 226 and during the first revolution of the drum 186, the tooth 226 engages the hook 228 and longitudinally pulls the rod 227, oscillating the arm 230 from the position illustrated, which 65 is its extreme right-hand position, toward the left around the pivot 231. The movement is sufficient to move the hook 228 beyond the path of the tooth 226, and the tooth travels on beyond the hook. The cam follower 232 is caused, by 70 this movement, to travel in a Z-shaped cam groove 233 in an extension 224 of the guide 189, causing the guide and the printing ribbon therein to be shifted transversely of the ribbon for the purpose above mentioned.

75 When the drum 185 begins to turn in the direc-

tion to wind the ribbon thereon, a similar disc 235 gives a longitudinal movement to a similar rod 236 pivoted to the arm 230 at 237 and oscillates it back to the position illustrated, thus shifting the ribbon back again to its former position.

5

Referring to Fig. 3, the ribbon 184, as will now be understood, moves step by step towards the right as viewed in the figure with the printing operation occurring along the center line 184a. 10 When the drum 185 is filled and the shift is made to wind the ribbon on the drum 186, the ribbon shifts over, that is to say, upwardly as viewed in Fig. 3, and begins to move toward the left and the printing operation occurs along the 15 center line 184b.

Thus as will be apparent, the ribbon will be repeatedly fed from end to end and along the side portion of the ribbon in one direction and back along the opposite side portion in the other direction until the ribbon is completely worn out in substantially all portions thereof, and thus this part of the mechanism can operate without attention for twice the usual time of mechanisms of this class in which the ribbon is merely alternated in direction from one end to the other and back again.

It will now be observed that after the character was printed, the printing magnet 13 remained partly energized through the lamp 23, 30 Fig. 2, and that the magnet 14 being fully energized operated to restore the printing cylinder to its normal position and to step ahead the paper strip and printing tape and to break the main circuit at the contacts 17-17 to de-energize both 35 magnets 13 and 14 preparatory to the printing of another character. As described in connection with Fig. 2, I have found that the operation of the apparatus may be rendered more positive by momentarily short-circuiting the contacts 17-17 40 during the opening thereof before finally breaking the main battery circuit controlled by the contacts 17-17, and the manner in which this is accomplished will now be described.

Referring to Fig. 15, the three-arm bell crank 152, which was described in connection with Fig. 12, is shown. When the bell crank 152 is given its clockwise movement by the lever 147, a third arm 155 thereon moves correspondingly and gives horizontal movement to the right to a ratchet pawl 240 pivoted at one end as at 241 to the bell crank arm 155 and constrained to rotate counter-clockwise by a spring 242 which holds its free or right-hand end into ratcheting engagement with the teeth of a ratchet wheel 243. Thus 55 the oscillatory movements of the bell crank 152 above described will at each movement ratchet the wheel 243 ahead one tooth.

An arm 244 pivotally supported at 245 is disposed above the ratchet wheel 243 and is provided with a pawl tooth 246 normally lodged in the spaces between the teeth of the ratchet wheel 243. Thus upon each step of the ratchet wheel, the arm 244 alternately rises and falls. Upon the upward movement of the arm 244, a roller 247 on the free end thereof raises a resilient switch arm 12 and causes the contact 29 thereon to engage a corresponding mating contact 29 on another resilient switch arm 9 to electrically connect the same to the two arms. The resilient switch arms 9 and 12 may be constructed as hereinbefore referred to in connection with similar arms by insulating them by means of blocks 248 secured to a support 249.

The clockwise movement of the bell crank 152 75

may be effected by the lever 147 and its pin 149 as above described. A counter-clockwise movement may be effected by the spring 165 reacting through the bell crank arm 167 when the pin 149 is retracted from the arm 152.

As will now be understood, the movement of the lever 147 which effects the opening of the contacts 17 through the coordinated elements including the pins 67, ratchet pieces 47, pins 48, bell crank 98, arm 91, cam surface 101 and armature 89 also closes a circuit around the contacts 17 by means of the contacts 29-29, the circuit connections having been illustrated and described in Fig. 2 and the coordinated elements actuated by movement of the lever 147 being the bell crank 152, ratchet elements 240 and 243, arm 244 and switch arms 12 and 9.

It will be observed that the magnet 14 by which the contacts 17-17 are opened tends to become de-energized by the opening of these contacts so that there may be in some cases a tendency for the contacts 17-17 not to clearly open but to "chatter". By throwing the short circuit around the contacts 17-17 through the contacts 29-29, the contacts 17-17 may become fully open and break the circuit at that point without chatter. By the arrangement of the parts above described, the continued re-setting movement of the lever 147, after it has closed the contacts 29-29, continues to rotate the ratchet wheel 243 to finally break or separate the contacts 29-29, thus breaking the main supply circuit from the battery 15, Fig. 2, in a manner and by a mechanism as described which is not susceptible of chattering, and de-energizing both magnets 13 and 14 whereupon all the parts of the apparatus which have not heretofore been re-set, now move to their normal or re-set position, and the entire apparatus is ready for another character-printing cycle.

From the foregoing description, it will now be clear that upon the reception of a single impulse or of a group of impulses in one or both of the magnets 7 and 8, a complete cycle of operations is initiated and performed and the apparatus reset to its original condition ready to receive another impulse or group of impulses. The energy for operating the apparatus through such a cycle is derived from a source local to the receiver, namely the battery 15. The energy for moving the type cylinder selectively is mechanical energy stored up in the receiver by the magnet 14 when energized to reset the apparatus for the reception of an impulse or impulses.

Thus in one aspect, it may be stated that the mechanical energy stored up at the end of a cycle by the magnet 14, is energy which operates upon the reception of impulses to initiate a cycle of operations, all of which occur in succession after which a sufficient quantity of energy is stored up, as a last part of the cycle of operations, to initiate the next succeeding cycle.

In Figs. 21 and 22 I have illustrated a modification of a part of the receiver of my invention and of which a simple description will suffice in view of the more complete description of the preferred form. In the form hereinbefore described, with reference to Fig. 3 and Fig. 1, the type cylinder 1 is rotated always in the same direction. Thus to print a "comma" character, the cylinder must be rotated through six character-printing positions, starting from the position 3 to bring the "comma" character in position to be printed.

According to the modification of Fig. 21, the cylinder is normally disposed with a neutral or starting or blank character space 400, Fig. 22, in what

may be called a middle position, and to print some of the characters the cylinder is rotated from one to four spaces either clockwise or counter-clockwise in combination with longitudinal movement as in the first form.

The longitudinal movement may be effected as described in connection with Fig. 3 by the bell crank arm 63. The rotary movement counter-clockwise (that is to say, with the upper side of the cylinder moving toward the left as viewed in Fig. 10 3), a similar mechanism may be employed comprising a rack bar 487 having teeth engaging a gear 488, the bar being moved step by step by the rod 55 as in the first form. To rotate the cylinder in the opposite direction, a second bar 15 489 having teeth on its upper side engageable with the gear 488 is given a vertical movement as viewed in Fig. 21 to engage its teeth with the gear, and by being secured as at 490 to the rod 55 raises the rod and the bar 487 connected thereto to 20 demesh the teeth of the latter with the gear. Thus upon movement of the bar 55, the rack bar 489 will turn the gear 488 in the opposite direction.

To shift the bars 489 and 487 as described, a 25 magnet 491 attracts an armature 492 pivoted at 493 and the end of the armature 492 engages a bell crank 494, pivoted at 495, having at the end of one arm a roller 496 engaging and rolling upon the rack bar 489. The center of the pivot 30 495 is disposed at the left of the roller 496 so that upon counter-clockwise movement given to the bell crank by the armature 492, the roller 496 will roll upon the rack bar 489 with a rising movement to elevate the same for the purpose 35 above described.

The bell crank is maintained in its rotated position by the engagement of another arm 497 thereof with a latch 498. When the bar 55 is returned by the restoring or resetting operation 40 hereinbefore described, an abutment 499 on the end of the rack bar 489 engages an upstanding arm 500 on the latch 498 which is pivoted at 501, rocking the latch and releasing the bell crank 494 and the latter is returned to its normal 45 position by a spring 502 connecting the bell crank 497 and the latch 498, whereupon the bar 489 may fall to its original position, providing that the magnet 491 has in the meantime been de-energized to permit the armature 492 to be 50 returned to its unattracted position which movement may also be effected by the spring 502. Thus whenever the magnet 491 is energized, the rack bar 489 will control the movement of the gear 488, and when it is unenergized the bar 487 55 will control the movement.

Any suitable circuit connections may be employed for energizing the magnet 491, either by a suitable electric impulse transmitted thereto from a distant sending station, or by energy supplied thereto from the local source 15, through contacts suitably closed before the beginning of the ratcheting movement.

It will be apparent now that by means of the arrangement of Fig. 21, the type bar, if it has its characters arranged as indicated for some of the characters in Fig. 22, may be rotated through a range of seven characters, the movement being to the extent of four characters on 65 each side of a central position whereas in the first described arrangement, see Fig. 1, the rotation was over an extent of six characters at one side of a starting position. This reduction in 70 rotary movement obviously shortens the period 75

of time required for the movement and speeds up the operation as a whole.

In either the described form or that employing a modification of Fig. 21, it will be observed that by sending impulses to both magnets 7 and 8 simultaneously, the type cylinder will rotate and move longitudinally, both movements occurring concurrently and thus the type cylinder is moved to its selective position with a screwing movement on all or a part of its selection movement.

Again, by employing the modification of Fig. 21, as will now be clear, since the rotary movement in either direction is over fewer character spaces, ratchet pieces 47 may be employed having fewer tooth spaces thereon, and therefore at the end of their maximum movement they can be reset in a shorter period of time, having less distance to travel to be returned to their original position. Thus both the time of position selecting and the time of restoring is shortened.

By reference to Figs. 7, 16, 14 and 15, which illustrate an actual apparatus in which my invention may be embodied, and which apparatus has been developed into somewhat diagrammatic form in Figs. 3 and 12, it will be seen that the apparatus may conveniently be assembled upon its frame comprising a base portion 300, a floor portion 301 spaced vertically thereabove and supported in spaced relation by suitable posts 302—302 and a vertical wall portion 303 standing or rising from an intermediate portion of the floor portion 301. As shown in Figs. 14 and 15, the paper strip and ribbon actuating mechanism 35 may be conveniently disposed on opposite sides of the wall 303.

As shown in Fig. 16 and partly in Fig. 7, the mechanism for selectively moving the type cylinder 1 may conveniently be mounted upon the floor portion 303; and as shown in Fig. 7, the magnets 13, 14, and 7 and 8 may conveniently be disposed between the floor portion 301 and the base 300, the magnet 13 and its frame being conveniently suspended from the underside of the floor portion 301, as may also the magnet 14 and its frame, and the magnets 7 and 8, see also Fig. 16, may conveniently be disposed on the upper side of the base 300.

The magnet 10, as indicated in Fig. 16, may be disposed at right angles to the floor portion 301 and may be disposed generally thereunder. To avoid complications of the drawings, this magnet has been illustrated in the horizontal position in Fig. 3, but it is believed that the construction thereof and of the correlated parts will be clear from Fig. 16 without further illustration or description.

As shown in Fig. 16, the roller 178, which controls the feed of the paper strip 125, may have upon its shaft or axis a hand wheel 310 by which the roller may be rotated manually to run the paper strip 125 ahead for obvious purposes.

In Fig. 7, a single magnet 14 is illustrated. In some instances I may employ two magnets, in which case the second magnet would be disposed directly behind the magnet 14 illustrated in Fig. 7. In such case, also, it would be preferred to provide two magnetic circuits, one for each magnet. As described hereinbefore, the magnetic circuit of the electro-magnet 14 comprises a horizontal element 311 by which it may be supported on the floor portion 303, a depending leg 312 and the magnet core and magnet armature 140; and these parts are preferably dupli-

cated except as to the armature 140, when two windings are employed.

Such a two-magnet construction is shown in Fig. 18 which may be considered as viewed from the plane 18 of Fig. 7 with the parts broken away at the pivotal bearing 139. The two magnet windings 14a—14a have a common yoke 320 and the armature 140 may be attracted by both magnets 14a—14a. The armature 140 has a central head portion 321 thereon transversely through which extends a short pin 322, the ends of the pin mounting the inner race elements 323—323 of ball bearings, the outer race elements of which 324—324 are supported in suitable bores in arms 325—325 of the common yoke 320.

The pin 322 corresponds to the pivot bearing element 139 in Fig. 7. By this construction, the armature 140 may pivot around the ball bearings described and furthermore, which is an important feature of this construction, the magnetism from the magnets 14a—14a flows not only through the armature 140 and yoke 320 but on its way from one to the other, flows into the head 321 and thence through the inner and outer bearing elements 323 and 324 and through the balls such as 326 therebetween.

The magnetism by attracting the balls and their race elements into tight engagement with each other, eliminates every trace of lost motion in these bearings, and at the same time, due to the ball type of bearing, does not introduce friction thereby; and furthermore, by this construction a continuous magnetic path of low reluctance is provided, the only air gap being that between the cores of the magnets 14a—14a and the armature 140. Thus a very efficient as well as silent and lost-motion proof magnetic circuit and armature mounting is provided having properties particularly suitable and advantageous in mechanisms of the kind under consideration.

The actual construction of the armature 35 of the magnets 7 and 8 is to be particularly noted. In the preferred construction, the armature comprises a portion 315 disposed opposite the core of the magnet, which portion is pivotally supported at 37, and a relatively slender rod portion 35 rising vertically therefrom, the upper end of which as plainly shown in Figs. 7 and 16 engages the arm 39 of the bell crank-form ratchet pawl supporting pieces. By supporting the magnet 7 on the base 300 and the ratcheting mechanism referred to upon the spaced floor 301, a considerable length of rod portion 35 may be provided which makes it possible to so proportion the length and diameter of the rod portions 35 that they may bend under the force applied thereto by the windings 7 and 8. Thus for a considerable movement of the upper ends of these rod portions 35 it is only necessary to move the armature portion 315 a very slight distance and the armature portion 315 may respond immediately to the impulses, followed by movement of the rod portion, the rod portion functioning as a resilient rectilinear bar spring. It will be observed that this movement of the rod portion 35 is distinctly different from that of an armature portion which merely moves under the influence of magnetism and is retracted by a spring, and in which the inertia of the parts must be continuously overcome, during their vibration, by the direct pull of the magnet.

The rod-like portions 35 have a natural frequency or period of vibration which may be made to correspond to the rate at which the impulses occur, and thus the effect of the magnetic im-

pulses from the magnets 7 and 8 may be described as that of keeping the rod-like armatures in vibration rather than of bodily moving them.

The armatures 35 may be retracted in any suitable manner but I prefer to retract them by springs 316-316, Fig. 16, acting through the bell crank arms 39-39.

As will be observed from an examination of the diagram of Fig. 2, the apparatus embodying my invention is at all times ready to receive impulses from a sending station and between periods of receiving, all of the circuits are dead. No manual operations need be performed to adapt the receiver to receive impulses and to print characters.

Such a receiver is particularly adapted to use with a plurality of like receivers where it may be desired to switch incoming impulses from one receiver to another, or where it may be desired to connect a number of receivers to the transmitting circuit.

Another advantage of my receiver is that there is no need to synchronize the impulses to the magnets 7 and 8. These impulses may come in sets or groups of impulses simultaneously or one set immediately succeeding another set.

Another advantage of my improved receiver is that at the end of the reception of a message by printing of characters and words, the paper tape may be run through the receiver to bring the end of the message out in a position to be easily read and torn off from the main supply of paper simply by sending to the receiver a succession of spacing impulses, that is, impulses which bring the division 2 of the type cylinder of Fig. 1 into selected position. It is believed that this feature of operation will be clearly understood without further description.

According to the above description, the receiver may print words on the paper strip, the letters of the words and the spaces between the words being selected by predetermined groups of impulses transmitted to the magnets 7 and 8 over the wires 4 and 5 respectively. If now the wires 4 and 5 be interchanged so that the magnets 7 and 8 are energized respectively by impulses over the wires 5 and 4, selection and printing will occur but the words so printed will be unintelligible and will be in the nature of a code. Again, such a coded message may be de-coded by maintaining the wires 4 and 5 thus respectively connected to the magnets 8 and 7 and sending over the wires 4 and 5 from a local transmitter at the receiving station a copy of the coded message. This will cause the words to be printed by the receiver in de-coded condition wherein the message may be clearly read. This transmission of decoding impulses may be confined to the local circuit of the receiver, and not sent out by the transmitter to other receivers which may at the time be connected to it in a communication system, by opening a simple switch (not shown) which will disconnect the local transmitter from its outgoing line or lines.

As an alternative decoding method, the coded message may be copied on an ordinary typewriter having the keys suitably rearranged so that when the keys are pressed in the sequence of the letters of the coded message, the typewriter will print the message de-coded.

To change the receiver to a coding receiver, it is only necessary to reverse the line connections as above stated and this can be done by an ordinary reversing switch and the connections such as indicated at 505 in Fig. 2, the switch parts

shown in solid lines being in the position for ordinary receiving and the dotted line position indicating the coding receiving position.

In the preferred arrangement, I prefer to employ two lines such as 4 and 5 between the sending and receiving stations and to transmit impulses over each line to the magnets 7 and 8 respectively. In some cases, however, I may prefer to transmit the impulses from the sending station over a single line. Such a system may be referred to as a single-wire system, and the system of Fig. 2 as a two-wire system. One form of a one-wire system is illustrated in Fig. 19.

The impulses coming into the receiver over the single line 509 are of two kinds, namely positive and negative, and the magnets corresponding to the magnets 7 and 8 of Fig. 2 are polarized magnets 507 and 508, one magnet responding to the positive impulses and the other to the negative impulses. As in connection with the form of Fig. 2, when only positive impulses are transmitted over a one line, say the line 4, there are obviously gaps between successive impulses. When a single line system such as Fig. 19 is employed, there will correspondingly be gaps between the positive impulses and these gaps may be occupied by the negative impulses. Thus the time of transmitting impulses over the single line system is not increased over that of the two line system.

In Fig. 20 a single line system similar to that of Fig. 19 is shown, but whereas the polarized magnets 507 and 508 of Fig. 19 are connected in series, they are connected in parallel in Fig. 20.

To those skilled in this art it will occur that the magnets 507 and 508 responding selectively to differences of polarity of the impulses received over the single line 509, may be constructed to respond to impulses of different lengths or of different frequencies etc. so that my invention is not limited merely to positive impulses as in Fig. 2 or to positive and negative impulses as in Figs. 19 and 20.

In Fig. 23 I have illustrated in simplified diagrammatic form, one manner of interconnecting a plurality of intercommunicating stations at each of which is a transmitter and receiver, indicated respectively by the letters T and R. The transmitter T may be of any suitable construction adapted to send over a single line impulses of positive and negative character and in suitable groups in correspondence with characters to be printed at the receiver R, and the receiver may be of the kind hereinabove described; and such receiver may comprise a pair of selection magnets 507 and 508 as in Fig. 19.

The circuit connections of Fig. 23 are so provided that an operator at any one of the stations upon throwing a switch may selectively connect any one of the receivers including his own into a circuit whereby he can immediately transmit thereto a message from his transmitter. For example, if an operator at the station indicated at 600 wishes to communicate with the station 601, he may rock the switch bar 603 clockwise to engage the contact 604 whereupon impulses may be transmitted from the transmitter at 600 through the contacts 603-604, wires 605 and 606 to the receiver at 601. Similarly, by rocking the switch bar 603 counter-clockwise to engage the contact 607, the operator at 600 may transmit a message to the receiver at 602 by impulses sent from the transmitter 600 over contacts 603-607, wires 608 and 609 to the receiver 602.

In a similar way, as will now be understood by those skilled in this art, the operator at either of the stations can select any one of the receivers and transmit a message thereto which will be received and recorded on a strip of paper by the receiver hereinabove described.

In Fig. 24 is illustrated another circuit of connections whereby an operator at a single transmitter such as 700 may selectively transmit a message to any one of a plurality of receivers such as 701, 702, 703, etc., or may simultaneously transmit a message to any number or all of them. At the station 700, there may be provided a corresponding plurality of single throw double pole switches 704, 705 and 706. Upon closing any one of these switches, the current impulses sent out by the transmitter T will be transmitted to the corresponding receiver and actuate the same to print a message as above described.

The impulses sent out on the system of Fig. 24 may be considered as impulses on a two-wire system, and those of Fig. 23 as impulses on a one-wire system as hereinbefore explained.

My invention is not limited to the exact details of construction shown and described. Many modifications and changes may be made therein without departing from the spirit of the invention or sacrificing its advantages.

I claim:

- 30 1. In an electric system and apparatus for communicating intelligence, an element selectively positionable by rotational and axial movements thereof, separate means for moving the element rotationally and axially, a pair of devices movable selected distances by selected numbers of step movements, connections between the devices and the said separate means for selectively controlling the extent of axial and rotational movements of the element by the separate means, and means including a pair of electro-responsive devices for step-moving the devices in accordance with selected numbers of electrical impulses transmitted to the electro-responsive devices.
- 45 2. In an electric system and apparatus for communicating intelligence, an element selectively positionable by rotational and axial movements thereof, separate resilient means for moving the element rotationally and axially, a pair of devices movable selected distances by selected numbers of step movements, connections between the devices and the said separate means for selectively controlling the extent of axial and rotational movements of the element by the separate resilient means, resilient means for moving the devices, and means including a pair of electro-responsive devices for effecting a step-by-step movement thereof in accordance with selected numbers of electrical impulses transmitted to the electro-responsive devices.
- 55 3. In an electric system and apparatus for communicating intelligence, an element selectively positionable by rotational and axial movements thereof, separate means for moving the element rotationally and axially, a pair of devices movable selected distances by selected numbers of step movements, connections between the devices and the said separate means for selectively controlling the extent of axial and rotational movements of the element by the separate means, means for moving the devices, and means including a pair of electro-responsive devices for effecting a step-by-step movement thereof in accordance with selected numbers of electrical impulses transmitted to the electro-responsive devices.
- 70 4. In an electric system and apparatus for communicating intelligence, an element selectively positionable by rotational and axial movements thereof, a first means for moving the element rotationally, a second means for moving the element axially, means including a pair of electro-responsive devices and a mechanism operable thereby for selectively controlling the extent of said axial and rotational movements of the element by said first and second means in accordance with selected numbers of electrical impulses transmitted respectively to the electro-responsive devices, and said first and second moving means operating respectively independently whereby the said rotational and axial movements may occur concurrently or successively in accordance with the concurrence or succession of the said selected numbers of electrical impulses.

5 5. In an electric system and apparatus for communicating intelligence, an element selectively positionable by rotational and axial movements thereof, a first means for moving the element rotationally, a second means for moving the element axially, means including a pair of electro-responsive devices for selectively controlling the extent of said axial and rotational movements of the element by said first and second means in accordance with selected numbers of electrical impulses transmitted to the electro-responsive devices, and a local source of power for effecting said movements of the element and rendered effective by the response of the electro-responsive devices.

10 6. In an electric system and apparatus for communicating intelligence, an element selectively positionable by rotational and axial movements thereof, separate means for moving the element rotationally and axially, a pair of devices movable selected distances by selected numbers of step movements, means for moving the devices, connections between the devices and said separate means permitting the devices to move relatively to the said means and for selectively controlling the extent of axial and rotational movement of the element by said separate moving means, the means for moving the devices including a pair of electro-responsive devices for controlling the extent of movement of the devices in accordance with selected numbers of electrical impulses transmitted to the electro-responsive devices.

15 7. In an apparatus for communicating intelligence, an element having a plurality of selective positions, means for moving the element to selected positions and a step-movement mechanism controlling the extent of movement of the element by said moving means, an electro-magnet for controlling the extent of movement of the said moving means in response to selected numbers of electrical impulses transmitted to the electro-magnet, the electro-magnet comprising an armature having a support adjacent the magnet and a relatively slender reed-like extension having a portion remote from the magnet associated with the step-movement mechanism.

20 8. In an apparatus for communicating intelligence, an element having a plurality of selective positions, means for effecting movement of the element to selected positions including a step-movement element and resilient means for moving it, an electro-magnet and armature-operated pawl mechanism for selectively controlling the extent of movement of the step movement element by the resilient moving means in response to selected numbers of electrical impulses transmitted to the electro-magnet, the resilient means

25 30 35 40 45 50 55 60 65 70 75 80 85 90 95

- comprising a transversely bending resilient element engaging at one portion thereof a portion of the step-movement element and at another portion remote therefrom connected to an oscillatory head, and means for oscillating the head in one direction to stress the resilient element.
9. In an apparatus for communicating intelligence, an element having a plurality of selective positions, means for effecting movement of the element to selected positions including a step-movement element, resilient means for moving it, an electro-magnet and armature-operated pawl mechanism for selectively controlling the extent of movement thereof in response to selected numbers of electrical impulses transmitted to the electro-magnet, the resilient means comprising a transversely bending resilient element engaging at one portion thereof a portion of the step-movement element and at another portion remote therefrom connected to an oscillatory head, and means for oscillating the head in one direction to stress the resilient element, said head oscillating means comprising a second resilient element opposed by the resilience of the first resilient element when stressed.
10. In an apparatus for communicating intelligence, an element having a plurality of selective positions, means for effecting movement of the element to selected positions including a step-movement element, resilient means for moving it, an electro-magnet and armature-operated pawl mechanism for selectively controlling the extent of movement thereof in response to selected numbers of electrical impulses transmitted to the electro-magnet, the resilient means comprising a transversely bending resilient element engaging at one portion thereof a portion of the step-movement element and at another portion remote therefrom connected to an oscillatory head, and means for oscillating the head in one direction to stress the resilient element, said head oscillating means comprising a second resilient element opposed by the resilience of the first resilient element when stressed, a portion of the head being movable into engagement with a portion of the step-movement element and to return the latter to a normal position upon oscillation of the head in the other direction, and means to oscillate the head in the other direction.
11. In an apparatus for communicating intelligence, an element having a plurality of selective positions, means for effecting movement of the element to selected positions including a step-movement element, resilient means for moving it, an electro-magnet and armature-operated pawl mechanism for selectively controlling the extent of movement thereof in response to selected numbers of electrical impulses transmitted to the electro-magnet, the resilient means comprising a transversely bending resilient element engaging at one portion thereof a portion of the step-movement element and at another portion remote therefrom connected to an oscillatory head, and means for oscillating the head in one direction to stress the resilient element, said head oscillating means comprising a second resilient element opposed by the resilience of the first resilient element when stressed; a portion of the head being movable into engagement with a portion of the step-movement element and to return the latter to a normal position upon oscillation of the head in the other direction, and means to oscillate the head in the other direction, and the opposing resilience of the two said resilient elements maintaining the said head portion in substantially

constant spaced relation from the corresponding engageable portion of the step-movement element in all selective step-movement positions thereof.

12. In an electric system and apparatus for communicating intelligence, a multi-character type element selectively positionable by rotational and axial movements thereof, means including a step-movement mechanism for selectively positioning the type element, electro-magnetic means responsive to selected numbers of impulses transmitted thereto for controlling the step-movements of the said mechanism to correspondingly effect selective positions of the type element, a printing mechanism, an actuating electro-magnet therefor energizable through a first set of switch contacts maintained disengaged by an electro-magnet and associated mechanism until cessation of said impulses, a printing ribbon and paper feeding mechanism associated with the printing mechanism, a reset mechanism, an actuating electro-magnet therefor energizable through a second set of contacts closed by mechanism associated with the printing electro-magnet and after energization of the latter, the reset mechanism comprising elements for restoring the step-movement mechanism to a normal position and for opening and holding open the first set of contacts and for operating the paper mechanism.

13. In an electric system and apparatus for communicating intelligence, a multi-character type element selectively positionable by rotational and axial movements thereof, means including a step-movement mechanism for selectively positioning the type element, electro-magnetic means responsive to selected numbers of impulses transmitted thereto for controlling the step-movements of the said mechanism to correspondingly effect selective positions of the type element, a printing mechanism, an actuating electro-magnet therefor energizable through a first set of switch contacts maintained disengaged by an electro-magnet and associated mechanism until cessation of said impulses, a printing ribbon and paper feeding mechanism associated with the printing mechanism, a reset mechanism, an actuating electro-magnet therefor energizable through a second set of contacts closed by mechanism associated with the printing electro-magnet and after energization of the latter, the reset mechanism comprising elements for restoring the step-movement mechanism to a normal position and for opening and holding open the first set of contacts and for operating the paper mechanism, and for temporarily closing a shunt circuit around said first set of contacts and then opening the shunt circuit.

14. In a typewriter mechanism, a type element, a paper strip and printing ribbon therefor, a printing hammer comprising a reciprocatory plunger adapted to strike a printing blow on one end, a tubular plunger guide, an axially adjustable head on the opposite end of the plunger externally of the guide, an axially adjustable stop on the guide upon which the head may impinge, means supporting the plunger at its head end, and means for moving the supporting means for communicating a printing movement to the plunger.

15. In a typewriter mechanism, a type element, a paper strip and printing ribbon therefor, a printing hammer comprising a reciprocatory plunger adapted to strike a printing blow on one end, a tubular plunger guide, a head on the opposite end of the plunger externally of the guide, an axially adjustable stop on the guide upon

- which the head may impinge, and means for communicating a printing movement to the plunger, said means comprising an oscillatory armature, an electro-magnet for oscillating the same, a head on the armature adjustable in the direction of movement thereof and normally engaging the head end of the plunger for moving the same when oscillated by the electro-magnet. 5
16. In an electric system and apparatus for communicating intelligence, a selectively positionable element, a selectively movable element, means for selectively moving the selectively movable element, means for communicating movement from the selectively movable element to the selectively positionable element to position the latter, comprising a pivoted lever element having one arm associated with the positionable element and another arm with the selectively movable element, the two arms being disposed at substantially the same relative angle as that between the directions of movement of the movable element and the positionable element. 10
17. In an electric system and apparatus for communicating intelligence, a rectilinearly movable selectively positionable element, a selectively rectilinearly movable element, means for selectively moving the selectively movable element, means communicating motion from the movable element to the positionable element comprising a pivoted lever element having one arm associated with the positionable element and another arm associated with the selectively movable element, the two arms being disposed at substantially the same relative angle as that between the directions 15 of movement of the movable element and the positionable element. 20
18. In an electric system and apparatus for communicating intelligence, a selectively positionable element, a selectively movable element, means for selectively moving the movable element, the two elements being constrained to move in directions at an angle to each other, means for communicating motion of the movable element to the positionable element, to selectively position it, whereby at all positions of the selectively movable element, a given extent of movement thereof will transmit to the positionable element an equal amount of movement or a predetermined multiple thereof. 25
19. In an electric system and apparatus for communicating intelligence, an element selectively positionable, a pair of devices movable selected distances by selected numbers of step movements, connecting means between the devices and the positionable element for controlling the selective movement thereof, means for moving the devices independently of movement of the connecting means, and means including a pair of electro-responsive devices for controlling the movement of the step movement devices, in accordance with selected numbers of electrical impulses transmitted to the electro-responsive devices, and an electric circuit to each of the electro-responsive devices over which the said electrical impulses may be transmitted from a distant station. 30
20. In an electric system and apparatus for communicating intelligence, an element selectively positionable, a pair of devices movable selected distances by selected numbers of step movements, connections between the step movement devices and the positionable element for selectively controlling the positioning thereof, and means including a pair of electro-responsive devices for controlling the movements of the step movement devices in accordance with selected 35 numbers of electrical impulses transmitted to the electro-responsive devices, the electro-responsive devices being polarized, and an electric circuit for energizing both of the electro-responsive devices over which electrical impulses may be transmitted to both devices in groups of impulses of selected numbers, the impulses of one group being of opposite polarity from those of the other group. 40
21. In an electric system and apparatus for communicating intelligence, an element selectively positionable, a pair of devices movable selected distances by selected numbers of step movements, connections between the step movement devices and the positionable element for selectively controlling the positioning thereof, and means including a pair of electro-responsive devices for controlling the movements of the step movement devices in accordance with selected 45 numbers of electrical impulses transmitted to the electro-responsive devices, the electro-responsive devices being polarized, and an electric circuit for energizing both of the electro-responsive devices over which electrical impulses may be transmitted to both devices in groups of impulses of selected numbers, the impulses of one group being of opposite polarity from those of the other group, and the impulses of one group alternating with those of the other in said circuit. 50
22. In an electric apparatus for communicating intelligence, a selectively positionable element, power supply means for moving the element, a step movement device for determining the extent of movement of the element, an electro-responsive device responsive to groups of electrical impulses transmitted thereto for controlling the step movement of the step movement device, and a telescopic connection between the step movement device and the selectively positionable element whereby the device may move independently of the movement of the element to a stepped position and the element may then move to a position determined by the position of the device. 55
23. In an apparatus for communicating intelligence, an element adapted to be moved to a plurality of selected positions, a mechanism selectively actuatable by a pair of electro-responsive devices each responsive to groups of electric impulses transmitted thereto over a corresponding one of a pair of transmission lines from a distant station, each group effecting a selective position of the said element, optionally operable switch means for interchanging the two lines with respect to the two electro-responsive devices to cause the same groups of impulses to effect correspondingly two different sets of selected positions of the said element. 60
24. In an intelligence communicating system and apparatus, a multi-character type element, an electrically operable printing mechanism, a paper step-feed mechanism, a selecting mechanism for selectively positioning the type element controlled by electrically actuatable means actuated by selective groups of electrical impulses transmitted thereto from a sending station, an electrically operable restoring device, a source of current, a mechanical energy storage means, the selecting mechanism being operable by stored energy upon reception by the selecting mechanism of transmitted impulses, a first switch means operable by the selecting mechanism, a circuit for the printing mechanism controlled by said first switch, a second switch means operable by the printing mechanism, a circuit for the restoring device controlled by said second switch means, 65
- 70
- 75

- the restoring device being electrically operable to actuate the paper step-feed mechanism and to restore the selecting mechanism and the first and second switch means and to store energy in 5 the storage means.
25. In an electric apparatus for communicating intelligence, a selectively positionable element, a mechanism for moving the element, a step movement device for determining the extent 10 of movement of the element, an electro-responsive device responsive to groups of electrical impulses transmitted thereto for controlling the step movement of the step movement device, and a connection between the step movement device 15 and the selectively positionable element whereby the step movement device may move independently of the movement of the element to a stepped position and the element may then move to a position determined by the position of the device.
20. 26. In an electric apparatus for communicating intelligence, a selectively positionable element, a mechanism for moving the element, a step movement device for determining the extent of movement of the element, an electro-responsive 25 device responsive to groups of electrical impulses transmitted thereto for controlling the step movement of the step movement device, and a telescopic connection between the step movement device and the selectively positionable element whereby the device may move independently 30 of the movement of the element to a stepped position and the element may then move to a position determined by the position of the device.
27. In an electric apparatus for communicating 35 intelligence, a selectively positionable element, a mechanism for moving the positionable element, a step movement mechanism for determining the extent of movement of the positionable element, an electro-responsive device responsive to groups 40 of electrical impulses transmitted thereto for controlling the step movement of the step movement mechanism, and a telescopic connection between an element of the positionable element moving mechanism and an element of the step 45 movement mechanism whereby the step movement mechanism may move independently of the movement of the positionable element moving mechanism to a step position, and the positionable element may then be moved to a position 50 determined by the position of the step movement mechanism.
28. In an apparatus for communicating intelligence, a type cylinder rotatable and axially movable to selective positions, an intermeshed gear 55 and rack associated with the cylinder for rotating it, means for propelling the rack, a movable element rotatively slidably associated with the cylinder to move it axially, means for moving the movable element, a pair of ratchetable elements 60 each having means for propelling it, a pair of movable pawl devices for controlling the extent of the ratcheting movement of the ratchetable elements, the pawl devices moving in accordance with movements of the armatures of a pair of 65 electro-magnets energized by selective numbers of electrical impulses transmitted thereto, and a telescopic connection between one of the ratchet elements and the rack and between the other ratcheting element and the movable element 70 whereby the ratchetable elements may move independently of and in advance of the rack and movable element to predetermine selectively the extent of rotative and axial movement of the cylinder.
75. 29. In an apparatus for communicating intelligence, a type cylinder rotatable and axially movable to selective positions, an intermeshed gear and rack associated with the cylinder for rotating it, means for propelling the rack, a movable element rotatively slidably associated with the cylinder to move it axially, means for moving the movable element, a pair of ratchetable elements each having means for propelling it, a pair of movable pawl devices for controlling the extent of the ratcheting movement of the ratchetable elements, the pawl devices moving in accordance with movements of the armatures of a pair of electro-magnets energized by selective numbers of electrical impulses transmitted thereto, and a telescopic connection between one of the ratchet elements and the rack and between the other ratcheting element and the movable element whereby the ratchetable elements may move independently of and in advance of the rack and movable element to predetermine selectively the extent of rotative and axial movement of the cylinder, and whereby the cylinder may be selectively positioned axially, or rotatively, or concurrently axially and rotatively. 5
30. In an apparatus for communicating intelligence, a type cylinder rotatable to selective positions, a gear associated with the cylinder, a pair of racks movable alternatively into mesh with the gear, means for selectively so moving the racks, means for propelling one rack when meshed to 35 rotate the cylinder in one direction and for propelling the other rack when meshed to rotate the cylinder in the opposite direction, and means for selectively determining the extent of movement of the rack to selectively rotatably position the cylinder. 25
31. In an apparatus for communicating intelligence, a type cylinder rotatable to selective positions, a gear associated with the cylinder, a pair of racks movable alternatively into mesh with the 40 gear, means for selectively so moving the racks, means for propelling one rack when meshed to rotate the cylinder in one direction and for propelling the other rack when meshed to rotate the cylinder in the opposite direction, and means for selectively determining the extent of movement of the rack to selectively rotatably position the cylinder. 45
32. In an apparatus for communicating intelligence, a type cylinder rotatable to selective positions, a gear associated with the cylinder, a pair of racks on opposite sides of the gear movable alternatively into mesh with the gear, means for selectively so moving them, means for propelling the alternatively meshed racks to rotate the cylinder 50 in corresponding opposite directions, and means for selectively determining the extent of movement of the racks to selectively rotatively position the cylinder, said last-named means including an electro-responsive device responsive to selected numbers of impulses transmitted thereto, and a step movement mechanism associated with the racks and controlled by the electro-responsive device. 55
33. In an apparatus for communicating intelligence, a type cylinder rotatable and axially movable to selective positions, a gear associated with the cylinder, a pair of racks on opposite sides of the gear movable alternatively into mesh with the gear, means for selectively so moving the racks, 70

- means for propelling the alternatively meshed racks to rotate the cylinder in corresponding opposite directions, a movable element associated with the cylinder to move it axially, means for so moving the movable element, means for determining the extent of movement of the racks and of the movable element to selectively rotatively and longitudinally position the cylinder, including a pair of electro-responsive devices responsive to selected numbers of electrical impulses transmitted thereto, a step movement mechanism associated with the racks and a step movement mechanism associated with the movable element, and the step movement mechanisms being controlled by the electro-responsive devices respectively.
34. In an apparatus for communicating intelligence, an element having a plurality of selective positions, means for moving the element to selected positions including a mechanism having a reciprocable element stepped in one direction and spring returned, an electro-magnet having an armature and a reedlike extension thereon responsive to impulses transmitted thereto, a portion of the extension relatively remote from the armature engaging the reciprocable element and adapted to move it under influence of the magnet in response to an impulse therein and resiliently bendable upon stopping of the reciprocatory element.
35. In an apparatus for communicating intelligence, an element having a plurality of selective positions, means for effecting movement of the element to selected positions, including a mechanism element movable to correspondingly selective distances, a resilient element for moving the mechanism element, a movable support for the resilient element, a second resilient element for moving the movable support to cause the first resilient element to resiliently engage the mechanism element whereby resilient force applied to the mechanism element may be rendered substantially constant throughout a range of movement of the mechanism element.
36. In an apparatus for communicating intelligence, an element having a plurality of selective positions, means for effecting movement of the element to selected positions, including a mechanism element movable to correspondingly selective distances, a resilient element for moving the mechanism element, a movable support for the resilient element, a second resilient element for moving the movable support to cause the first resilient element to resiliently engage the mechanism element whereby resilient force applied to the mechanism element may be rendered substantially constant throughout a range of movement of the mechanism element, means for moving the movable support in the reverse direction to stress the said second resilient element, a portion of the movable support being disposed adjacent a portion of the mechanism element and engageable thereby to transmit its reverse movement thereto, the two opposing resilient elements maintaining said portion of the movable support substantially a constant distance from the said portion of the mechanism element at substantially all positions of the latter in a range of movement.
37. In an electric system and apparatus for communicating intelligence, a multi-character type element, electrically controlled mechanism responsive to the reception of selective groups of electrical impulses transmitted thereto for selectively positioning the element for the performance therewith of a printing operation, an electrically actuated mechanism for feeding a paper strip to the type element in association with a printing ribbon, an electrically actuated printing mechanism, an electrically actuated restoring mechanism, means automatically responsive to termination of the energization of the selective mechanism by one or more impulses, to effect actuation of the printing mechanism, the resetting mechanism, the paper feed mechanism, and the de-energization of the printing mechanism and the resetting mechanism, in a predetermined cyclical sequence.
38. In an electric system and apparatus for communicating intelligence, a multi-character type element, electrically actuated means for selectively positioning the element for the performance thereby of a printing operation, a mechanism for dispensing a paper strip and a printing ribbon in association with the type element, and comprising a pair of tape winding drums, drum rotating mechanism for alternately rotating the drums to wind up the tape on one and unwind it from the other, a tape engaging element between the drums and movable to move the tape in the transverse direction to shift the same relative to the type element, means for periodically so shifting the tape engaging element comprising a device associated with the element, and reciprocatory connections between the device and the drum rotating mechanism operable thereby at predetermined wound conditions of the tape on either drum.
39. In an electric system and apparatus for communicating intelligence, a multi-character type element, electrically actuated means for selectively positioning the element for the performance thereby of a printing operation, a mechanism for dispensing a paper strip and a printing ribbon in association with the type element, electrically actuated means for effecting a printing operation on the paper strip after each positioning of the element, electrically actuated means for operating the paper dispensing mechanism after each printing operation and for moving the tape longitudinally in alternate directions and between reversals thereof, shifting the tape in the transverse direction to cause the printing operations to be effected on two parallel portions of the ribbon adjacent opposite edges thereof.
40. In a typewriter mechanism, a type element provided with a plurality of elevated type characters and a less elevated "space" character and movable to selective character positions, a paper strip and printing ribbon, a printing hammer comprising a reciprocatory plunger adapted to strike a printing blow on one end, a plunger guide, a head on the opposite end of the plunger, means for communicating a free projectile movement to the plunger to effect a printing operation, the head being adapted to stop plunger printing movement by engagement with a portion of the guide when the type cylinder is in the "space" character position and to clear the said guide portion when the type element is in an elevated character position.
41. In an electric system and apparatus for communicating intelligence, a selectively positionable element, means for moving the positionable element, a selectively movable element, means for selectively moving the selectively movable element, the directions of movement of the positionable element and selectively movable element being at an angle to each other, means for communicating the extent of movement of the selectively movable element to the selectively po-

- sitionable element to position the latter, comprising a pivoted lever element having one arm associated with the positionable element to move it and another arm associated with the selectively movable element, the two arms being disposed at substantially the same relative angle as that between the directions of movement of the movable element and the positionable element.
42. In an intelligence communicating system and apparatus, a multi-character type element, an electrically actuatable printing mechanism, an electrically actuated paper step-feed mechanism, a mechanically operated mechanism for moving the type element to a plurality of different selective printing positions, an electrically actuated selective mechanism for selectively determining the positions of the type element and selectively responsive to an electro-magnetic means actuatable by selective groups of electrical impulses transmitted thereto from a distant station, an electrically actuated restoring device, and automatic electric means responsive to cessation of transmitted impulses to effect completion of a cycle of operations including a character selecting operation by the selective mechanism, closing the circuit to the printing mechanism to effect a printing operation, closing the circuit to the restoring device to effect a restoring of the parts to their original position and to effect actuation of the paper feed mechanism and to effect the storing up of mechanical energy for operating the type moving mechanism in the next succeeding cycle and to effect opening of the circuits to the printing mechanism and the restoring device.
43. In an apparatus for communicating intelligence, an element having a plurality of selective positions, means for effecting movement of the element to selective positions including a mechanism controlled by an electro-magnet responsive to selective groups of impulses transmitted thereto from a distant station, electrically actuatable intelligence communicating apparatus operative after completion of the transmission of a group of said impulses, an auxiliary electro-magnet energized by said impulses, a switch normally tending to close and remain closed adapted to be held in open position by the auxiliary electro-magnet responsive to said impulses, for delaying energization of said intelligence communicating apparatus until cessation of said impulses, a mechanism for holding said switch in open position until the auxiliary electro-magnet is energized, the mechanism normally tending to move to permit the switch to close and latch means associated with said switch and said mechanism for maintaining said holding mechanism in open switch position until said auxiliary magnet is energized.
44. In an apparatus for communicating intelligence, an element having a plurality of selective positions, means for moving the elements to said positions selectively including a step movement mechanism controlled by an electro-magnet responsive to selective groups of impulses transmitted thereto from a distant station, means for returning the step movement mechanism to its normal position after a selecting movement including a pivoted lever engageable with a portion of the mechanism, a bearing support for the lever, an electro-magnet having a movable armature, a link element pivotedly connected to the lever, and a spring connecting the armature and the link.
45. In an apparatus for communicating intelligence, an electric mechanism selectively cyclically responsive to transmitted groups of electrical impulses, a local source of electrical energy, a restoring electro-magnet energizable thereby to restore the elements of the electrical mechanism to normal positions, after a cyclical response, and to break its own energizing circuit, means to maintain the restoring magnet energized until full completion of the restoring operation including means operable in an early portion of the restoring operation to close a switch in the energizing circuit of the restoring magnet and to open the switch at the end of the restoring operation.
46. In an apparatus for communicating intelligence, an electric mechanism selectively cyclically responsive to transmitted groups of electrical impulses, a local source of electrical energy, a restoring electro-magnet energizable thereby to restore the elements of the electrical mechanism to normal positions, after a cyclical response, and to break its own energizing circuit, means to maintain the restoring magnet energized until full completion of the restoring operation including means operable in an early portion of the restoring operation to close a switch in the energizing circuit of the restoring magnet and to open the switch at the end of the restoring operation, said means comprising a movable switch closing member, having an abutment portion, a star wheel engaging the abutment portion and a movable ratchet means to rotate the star wheel said ratchet means being movable by the restoring magnet.
47. In an intelligence communicating apparatus, a multi-character type cylinder, a rack pinion associated with the cylinder, a rack device comprising two rack tooth portions having spaced substantially parallel rows of confronting rack teeth on opposite sides of the pinion, means for moving the rack portions alternatively into engagement with the pinions, and electro-magnetically operated mechanism responsive selectively to groups of electrical impulses transmitted thereto to selectively move the rack portions selective distances in one direction to selectively rotate the cylinder selective fractions of a revolution in alternate directions.
48. In an apparatus for communicating intelligence, a power source, a circuit supplying power from the source to the apparatus, an intelligence communicating selectively positionable element, an electric mechanism comprising a pair of selectively positionable devices movable to selective positions under the control of a pair of electro-magnets responsive to selective groups of electric impulses transmitted thereto from a distant station, an electrically actuated mechanism for returning the devices to normal position, an equalizing bar engageable by portions of the devices upon their return movement, a lever pivotally connected to the bar and movable thereby, a switch contact adaptable to be operated through the agency of the moving lever and controlling the said power supply circuit.
49. In an apparatus for communicating intelligence, a power source, a circuit supplying power from the source to the apparatus, a multi-character type cylinder selectively positionable by axial and rotational movements, an electric mechanism comprising a pair of selectively positionable ratcheting devices movable to selective positions under the control of a pair of electro-magnets responsive to selected groups of electrical impulses transmitted thereto from a distant station, to control the extent of rotational movement.

- and axial movement of the cylinder, an electrically actuated mechanism for returning the ratcheting devices to normal positions an equalizing bar engageable by portions of the ratcheting devices upon the return movement, a lever pivotally connected to the bar and movable thereby, and switch contacts adapted to be opened through the agency of the moving lever and controlling the said power supplying circuit.
5. 50. In a system and apparatus for communicating intelligence, an element movable to selective intelligence communicating positions, an automatic electric mechanism for selectively positioning the element and effecting an intelligence communicating operation controlled by a pair of electro-magnets responsive to selective groups of electrical impulses transmitted thereto over a transmitting circuit, a local source of energy and a local electric circuit for the mechanism controlled by electrical contact mechanism to cyclically close the local circuit and operate the mechanism and open the circuit, in response to the reception of a selected group of impulses, and an impulse transmitting circuit normally open and closeable for the transmission of impulses to the pair of electromagnets.
5. 51. In an electric system of apparatus for communicating intelligence, a local current source and circuit connections and an electric mechanism actuated thereby for automatically selectively effecting any one of a plurality of intelligence communications, a pair of electro-magnets jointly controlling the selectivity of the mechanism and responsive to selected groups of electric impulses transmitted thereto over a transmitting circuit, from a distant station, the local circuit and transmitting circuit both being normally open and the local circuit being closed through the agency of the said electro-magnets upon energization thereof by line impulses.
10. 52. In an electric system and apparatus for communicating intelligence, an automatic printing mechanism operable through a predetermined cycle of operations to print any one of a plurality of letters selectively in response to any one of a plurality of selective groups of impulses transmitted from a distant station, the mechanism comprising a printing electro-magnet and a restoring electro-magnet for restoring the mechanism to normal position after a cycle thereof, a local current source, a local circuit and circuit connections and circuit controlling contacts, the printing magnet and the restoring magnet being adapted to be connected in parallel with the local source, a resistance unit, certain contacts being operable upon reception of a selective group of impulses to connect the printing magnet to the source and the resistance unit in series with the restoring magnet when the printing magnet is energized, and for connecting the restoring magnet to the source and the resistance unit in series with the printing magnet when the printing magnet operates.
15. 53. In a typewriter mechanism, a type element, a paper strip and printing ribbon therefor, a printing hammer comprising a reciprocatory plunger adapted to strike a printing blow on one end, a tubular plunger guide, an axially adjustable head on the opposite end of the plunger externally of the guide, an axially adjustable stop on the guide upon which the head may impinge, means supporting the plunger at its head end, means for moving the supporting means for communicating a printing movement to the hammer, and a stop for the supporting means whereby the moving plunger may leave the supporting means by inertia to effect the printing blow.
20. 54. In a typewriter mechanism, a type element, a paper strip and printing ribbon therefor, a printing hammer comprising a reciprocatory plunger adapted to strike a printing blow on one end, a tubular plunger guide, a head on the opposite end of the plunger externally of the guide, an axially adjustable stop on the guide upon which the head may impinge, and means for communicating a printing movement to the hammer, said means comprising an oscillatory armature, an electro-magnet for oscillating the same, a head on the armature adjustable in the direction of movement thereof for normally engaging the head end of the plunger for moving the same when oscillated by the magnet, and a stop for the armature whereby the moving plunger may leave the armature head by inertia to effect the printing operation.

WILLIAM C. ROE.
